CLAIM

The ornamental design for a plant box for viewing roots, as shown and described.

DESCRIPTION

FIG. 1 is a perspective view of a plant box for viewing roots, showing my new design thereof;

FIG. 2 is a top plan view thereof;

FIG. 3 is a bottom plan view thereof;

FIG. 4 is front-elevational thereof;

FIG. 5 is a rear-elevational thereof;

FIG. 6 is a right side-elevational view thereof;

FIG. 7 is a left side-elevational view thereof; and,

FIG. 8 is a cross-sectional view taken substantially along line 8—8 of FIG. 2.

FIG. 1

FIG. 2

FIG. 3

FIG. 6

FIG. 7
